UNITED STATES PATENT OFFICE

106,115

DESIGN FOR A COMBINATION COASTER AND ASHTRAY

Joseph Edgar Hines, Indiana, Pa.

Application April 8, 1937, Serial No. 68,631

Term of patent 7 years

To all whom it may concern:

Be it known that I, Joseph Edgar Hines, a citizen of the United States and a resident of Indiana, in the county of Indiana and State of Pennsylvania, have invented a new, original, and ornamental Design for a Combination Coaster and Ashtray, of which the following is a specification, reference being had to the accompanying drawing, forming part thereof.

Figure 1 is a top plan view of a combination coaster and ashtray, showing my new design.

Figure 2 is an elevational view thereof.

Figure 3 is a view in cross section through the center of the article.

I claim:—

The ornamental design for a combination coaster and ashtray, as shown.

JOSEPH EDGAR HINES.
